UNITED STATES PATENT OFFICE.

JOHN EDWARD EVANS, OF NEW YORK, AND FRANCIS H. GRIFFITHS, OF YONKERS, NEW YORK, ASSIGNEES TO THE RELIABLE AUTOMATIC SPRINKLER COMPANY, INC., OF NEW YORK, N. Y., A CORPORATION OF NEW YORK.

DRY-PIPE VALVE.

Application filed October 26, 1923. Serial No. 670,862.

To all whom it may concern:

Be it known that we, JOHN EDWARD EVANS and FRANCIS H. GRIFFITHS, citizens of the United States, and residents of New York, county of New York, State of New York, and Yonkers, county of Westchester, State of New York, respectively, have invented an Improvement in Dry-Pipe Valves, of which the following description, in connection with the accompanying drawing, is a specification, like characters on the drawing representing like parts.

This invention relates to dry-pipe valves and particularly to a latch device for holding the water and air valves open after they have been tripped.

One of the objects of the invention is to provide an improved latch device for this purpose which is carried by the air valve and is constructed so that it is moved into operative position to lock the air and water valves open by the final opening movement of the air valve.

Another object of the invention is to provide an improved latch for this purpose which is constructed so that after it has been moved into its locking position by the movement of the air valve it will be maintained in such position by the locked air valve. The construction of the device is such that after the air and water valves are locked in their open position and the latch is thereby locked in its locking position said latch can be released only by removing the hand-hole cover plate with which dry-pipe valves are usually provided and through which access may be had to the working parts thereof.

Other objects of the invention will be more fully hereinafter described.

In the drawings wherein we have shown a selected embodiment of our invention, Fig. 1 is a vertical sectional view through a dry-pipe valve embodying our invention; showing the water and air valves closed;

Fig. 2 is a view partly in vertical section of said dry-pipe valve showing the air and water valves locked in their open position.

The dry-pipe valve herein illustrated is of the usual type which comprises a casing 1 having a water inlet 2 terminating in a water valve seat 3 and an outlet 4 which leads to the system. The water inlet is controlled by a water valve 5 as usual in dry-

pipe valves, said water valve being herein shown as carried by a swinging member 9 that is pivoted to the casing as shown at 6. The air valve which holds the water valve closed is indicated generally at 7 and it seats upon the air valve seat 8, the latter being herein shown as situated in an inclined plane relative to the water valve seat 3.

The air valve, which is subjected to the air pressure in the system, is pivotally mounted on the swinging member 9 as shown at 10 and is of larger area than the water valve, as usual in dry-pipe valves, so that when the valves are seated a relatively small air pressure in the system will suffice to hold the water valve closed against the higher water pressure.

It will be observed that the air valve is pivotally mounted on the water valve structure so that when the water valve opens from the position shown in Fig. 1 into that shown in Fig. 2 the air valve will be carried with it. In order to guide the air valve in its opening movement the latter is provided with an extension 11 carrying a guide roll 12 which rides on a guiding surface 13 formed on the casing, this guiding surface being so shaped as to cause the air valve to swing into the position shown in Fig. 2 relative to the water valve when the valves are opened.

14 indicates a pivotally mounted latch which functions to hold the air valve from becoming seated again if it is lifted off its seat slightly, this being a feature common to dry-pipe valves. Associated with the latch 14 is a drip valve 15 which is normally held open by the latch when the valves are closed thus allowing the neutral chamber 16 to be drained, but which is closed when the valves lift and the latch becomes operative all as usual in dry-pipe valves.

The present invention relates to a novel latch device for holding the water and air valves in their open position shown in Fig. 2 after they have been moved into such position by the giving way of a sprinkler head or some other cause. The latch is indicated at 17 and it is shown as pivotally mounted on the pin 18 on which the roll 12 is journaled. This latch co-operates with an abutment face 19 on a projection or abutment 20

that extends from the removable cover 21 of the hand-hole through which access to the valves is obtained.

When the valves are closed the latch 17 rests against the air valve as shown in Fig. 1 and means are provided whereby when the valves are opened the latch is thrown into operative relation to the abutment face 19 by the final opening movement of the air valve. For this purpose the latch has rigid therewith a laterally-extending tail 22 which is adapted to engage an abutment face or ledge 23 formed on the casing 1 just before the valves reach their completely-open position. The engagement of the tail 22 with the ledge 23 causes the latch to be swung positively away from the air valve and into a position in which it rests against the support 24 and with the end thereof situated opposite the abutment face 19, as shown clearly in Fig. 2. The latch is held by gravity in its operative position against the support 24 and co-operates with the abutment face 19 to hold the valves positively in their open position.

The lug or projection 20 on which the abutment face 19 is formed also acts as a support for the air valve when the latter is open, said abutment having the supporting face 25 against which the air valve rests. This projection 20 is carried on the hand-hole cover 21 so that when said cover is removed in order to reset the valve the abutment face 19 will also be removed thus freeing the latch and permitting the valves to be closed.

It will be observed that in this construction the latch is moved into its operative position by the final opening movement of the air valve and that when the latch has been thus carried into its operative position it is held thereby the locked air valve and the latter, therefore, cannot be reset until the hand-hole cover 21 has been removed.

While we have illustrated herein a selected embodiment of our invention we do not wish to be limited to the constructional features disclosed.

We claim:

1. In a dry-pipe valve, the combination with a casing, a pivotally mounted water

valve therein and an air valve pivotally carried by the water valve, of a latch carried by the air valve, an abutment co-operating with said latch to hold the air valve open, and means to swing the latch into operative position by the final opening movement of the air valve. 55

2. In a dry-pipe valve, the combination with a casing, a pivotally mounted water 60 valve therein and an air valve pivotally carried by the water valve, of a latch carried by the air valve, an abutment co-operating with said latch to hold the air valve open, and means to swing the latch into operative 65 position by the final opening movement of the air valve, said latch being held in such operative position by the locked air valve.

3. A dry-pipe valve comprising a casing, 70 a pivotally mounted water valve, an air valve pivotally carried by the water valve and a latch carried by the air valve, said casing having a projection which constitutes a rest for the air valve when the latter is open and also an abutment to co-operate 75 with the latch to lock the air valve in open position.

4. A dry-pipe valve comprising a casing having a hand-hole and a removable cover therefor, a pivotally mounted water valve, 80 an air valve pivotally carried by the water valve, and a latch carried by the air valve, said cover having a projection which constitutes a rest for the air valve when the latter is open and also having an abutment 85 to co-operate with the latch to hold the air valve in open position.

5. A dry-pipe valve comprising a casing, 90 a water valve pivotally mounted therein, an air valve pivotally carried by the water valve, a latch pivotally carried on the air valve and an abutment carried by the casing with which the latch co-operates to hold the air valve open, said casing having a ledge 95 with which the arm engages during the final opening movement of the air valve thereby to swing the latch into operative position.

In testimony whereof, we have signed our names to this specification.

JOHN EDWARD EVANS.
FRANCIS H. GRIFFITHS.
